O. F. FORSBERG

CONTACT BANK FOR COORDINATE SWITCHES

Filed Feb. 23, 1923

Inventor:
Oscar F. Forsberg,

by C.W. Adams Atty.

UNITED STATES PATENT OFFICE.

OSCAR F. FORSBERG, OF YONKERS, NEW YORK, ASSIGNOR TO WESTERN ELECTRIC COMPANY, INCORPORATED, OF NEW YORK, N. Y., A CORPORATION OF NEW YORK.

CONTACT BANK FOR COORDINATE SWITCHES.

Application filed February 23, 1923. Serial No. 620,629.

To all whom it may concern:

Be it known that I, OSCAR F. FORSBERG, a citizen of the United States, residing at Yonkers, in the county of Westchester, State 5 of New York, have invented certain new and useful Improvements in Contact Banks for Coordinate Switches, of which the following is a full, clear, concise, and exact description.

10 This invention relates to improvements in banks of contacts such as are used in machine switching devices.

More particularly it refers to a bank of active contacts employed in the coordinate 15 type of switch disclosed in the British Patent No. 183,438, issued to Western Electric Company, Limited, accepted September 6, 1923.

The object of the invention is to provide 20 an improved bank of contacts together with a fastening device for such bank which will be simple, efficient and cheap to manufacture.

A feature of this invention is the provision 25 of a contact bank comprising active contact members embedded and secured in a moulded strip of insulating material, so formed as to greatly facilitate the assembly of the device of which it forms a part.

30 Another feature is in the provision of metal plates for reenforcing the contact strip.

Other features of the invention will appear 35 from the following description and the claims appended thereto, reference being had to the accompanying drawings in which Fig. 1 is a right-hand side and partial assembly view of a coordinate switch showing the bar supporting the contact strips in cross-section, Fig. 2 is a plan view thereof, Fig. 3 is a detail view of Fig. 1 but showing a reenforcing plate and a portion of the bank partially cut away so as to show more clearly the card supports in position in the 40

molded groove and the flattened portion of the active contact wires anchored in the insulation, Fig. 4 is an enlarged plan view of the locking device showing the fastening portion of four contact strips held in position on the supporting bar, and Fig. 5 is a front and partial view of a set of active and passive contacts showing the active contacts attached to their supports and the camming card in normal non-operated position.

The strips of contacts shown in Figs. 1, 2 and 3 comprise a rectangular shaped bar 10 preferably made of plastic insulating material in which the contact wires 11, 12, 13 and 11', 12', 13', etc. are anchored by means 60 of flattened portions at 14, 15 and 16 shown in the sectional view of Fig. 2, and in the cut away portion of Fig. 3. The contact wires 11, 12, 13 and 11', 12', 13', etc. are preferably arranged in sets as shown in 65 Figs. 1 and 3 and for each set there is provided a card support 19, 20, 21, etc., each of which is positioned in its respective recess 17, 18, etc., molded in one side of the insulating bar 10 and held therein by means 70 of the reenforcing metal plates 23 and 24 which are rigidly attached, one on each side of the insulating bar 10 by means of eyelets 25, 26, 27, etc.

The fixed end portion of each of the card supports 19, 20, 21, etc. terminates in the shape of a ring 19' which is made to fit tightly into the molded recess of the insulating bar and around the eyelets used for uniting the reenforcing plates 23 and 24 and 75 insulating bar 10 thereby securing the card support against any lengthwise movements.

80 The reenforcing plate 23 is arranged in a lengthwise groove 29 molded in the insulating bar 10. The plate 24 is made channel-shaped and along one of the sides are made a number of notches 30 which register with the grooves 17, 18, etc., of the insulating support 10. The card supports thread through the notches 30 and are supported thereby 85 when acted upon by the resistance of the active contact wires or when acted upon by the lifting fingers as shown at 37 of Fig. 1.

The coordinate switch above referred to 90 comprises generally a plurality of coaxially disposed strips of contacts 10 which are positioned on the supporting notched bar 34 held securely on the switch frame not shown.

95 The strips 10 shown in Fig. 4 are securely held on the bar 34 by means of a notched disc 35 which is rotatably mounted on pivot 38 screwed in the bar 34. The notch 36 of disc 35 is provided to make possible the removal of any contact strip 100 in that group individually. In that event, it is only necessary to loosen the screw 38 and to rotate the disc until its notched portion is in juxtaposition with the fastening 105 portion of the bank to be removed. Simi- 110

larly, for assembling the banks on their supporting bar, the disc is rotated alternatively so as to move its notched portion with respect to the fastening end portion 5 of each bank. When the banks are in position, the disc is then rotated until its notched portion is in the position shown in Fig. 4 and the screw 38 is then tightened.

What is claimed is:

- 10 1. In a switch structure, the combination of a block of insulating material, sets of contacts anchored therein, a plurality of grooves therein for locating a plurality of supporting springs, and an abutment at each end of said block integrally formed therewith for locating said block on its supporting bar in the switch frame.
- 20 2. In a contact bank, the combination of an oblong shaped insulating block for supporting a plurality of sets of active contact wires, a plurality of supporting springs arranged at intervals in grooves therein, and means attached to said block for securing said supporting springs collectively.
- 25 3. In a contact bank for a coordinate switch, the combination of a molded block of insulating material for supporting sets of active contacts, a plurality of supporting springs located in grooves therein, and 30 a channel-shaped band of metal securing said springs in said grooves.
- 35 4. In a contact bank, the combination of a molded block of insulating material, a plurality of grooves molded therein at intervals in which supports are positioned, a channel-shaped band of metal attached to said block securing said supports in said grooves, and means along one edge of said

bank for retaining said supports in position on said bank.

5. In a coordinate switch structure, a strip of active contacts comprising a block of insulating material, contacts moulded therein, grooves molded at intervals therein for locating a plurality of supporting springs, a metal band on one side of said block for reenforcing the same, another plate on the opposite side for reenforcing said block and for securing said supports in position thereon, means for fastening said plates on said block and to assist in retaining said supports in the grooves of said block.

6. In a contact device, a rigid strip of moulded insulating material with a plurality of sets of spring contacts moulded therein and projecting therefrom, a corresponding plurality of supporting springs placed in suitable grooves moulded in said strip and secured thereto by rivets.

7. In a contact device, a rigid strip of moulded insulating material with a plurality of sets of spring contacts moulded therein and projecting therefrom, a corresponding plurality of supporting springs placed in grooves moulded in said strip, a reenforcing bar with a corresponding plurality of notches placed over said strips and said supporting springs, and a corresponding plurality of securing means for fastening the whole together to form a unitary structure.

In witness whereof, I hereunto subscribe my name this 16 day of February A. D., 1923.

OSCAR F. FORSBERG.
